(57) **CLAIM**

I claim the ornamental design for a hand guard for power tools, as shown and described.

DESCRIPTION

FIG. 1 is a perspective view of a hand guard for power tools in an assembled configuration;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the hand guard for power tools that do not form part of the claimed design.
